STAND OFF INSULATOR

Maurice G. Knoy, West Lafayette, Ind., assignor to
Rostone Corporation, Lafayette, Ind., a corporation of
Indiana

Filed Aug. 17, 1964, Ser. No. 81,367

Term of patent 14 years

(Cl. D26—10)

FIG. 1.

FIG. 2.

FIG. 3.

FIG. 4.

FIG. 6.

FIG. 5.

fig.7.

fig.8.

fig.9.

fig.10.

FIG. 11.

FIG. 12.

FIG. 13.

FIG. 14.

FIG. 16.

FIG. 15.

FIG. 1 is a front elevational view of a stand-off insulator, showing one form of my new design wherein the height and diameter are substantially equal, and one end has four attachment inserts and the other end has two attachment inserts, the rear being substantially a mirror image of the front;

FIG. 2 is a side elevational view of the form shown in FIG. 1, the opposite side being substantially a mirror image thereof;

FIG. 3 is an end elevational view of the form shown in FIG. 1, taken from the top in FIG. 1, showing four attachment inserts;

FIG. 4 is an end elevational view of the form shown in FIG. 1, taken from the bottom in FIG. 1, showing two attachment inserts;

FIG. 5 is a cross-sectional view of the form shown in FIG. 1, taken on the line 5—5 in FIG. 1;

FIG. 6 is a cross-sectional view of the form shown in FIG. 1, taken on the line 6—6 in FIG. 1;

FIG. 7 is a front elevational view of a stand-off insulator, showing another form of my new design wherein the height is greater than the diameter and each end has one attachment insert, the rear being substantially a mirror image of the front;

FIG. 8 is a side elevational view of the form shown in FIG. 7, the opposite side being substantially a mirror image thereof;

FIG. 9 is an end elevational view of the form shown in FIG. 7, the other end being substantially a mirror image thereof;

FIG. 10 is a cross-sectional view of the form shown in FIG. 7, taken on the line 10—10 in FIG. 7;

FIG. 11 is a front elevational view of a stand-off insulator, showing another form of my new design wherein one end has four attachment inserts and the other end has two attachment inserts, and wherein the insulator includes a central cylindrical column, the rear being substantially a mirror image of the front;

FIG. 12 is a side elevational view of the form shown in FIG. 11, the opposite side being substantially a mirror image thereof;

FIG. 13 is an end elevational view of the form of FIG. 11, taken from the top in FIG. 11, showing four attachment inserts;

FIG. 14 is an end elevational view of the form of FIG. 11, taken from the bottom in FIG. 11, showing two attachment inserts;

FIG. 15 is a cross-sectional view of the form shown in FIG. 11, taken on the line 15—15 of FIG. 11, and

FIG. 16 is a cross-sectional view of the form shown in FIG. 11, taken on the line 16—16 of FIG. 11.

The design is characterized by the generally spool shape of the insulator body, composed of two axially-spaced parallel round end-walls with locally thickened portions about the positions of the attachment inserts, and axially-extending strut walls between the end walls and comprising prominent radially-disposed webs at rectangularly spaced positions about the axis of the body.

This application is a continuation in part of my copending application Serial No. D. 76,757, filed September 27, 1963, now abandoned.

I claim:

The ornamental design for a stand-off insulator, as shown and described.
